(57) **CLAIM**

The ornamental design for a transparent bumper guard, as shown and described.

DESCRIPTION

FIG. 1 is a top plan view of a transparent bumper guard showing my new design;

FIG. 2 is a rear elevational view thereof;

FIG. 3 is a right side elevational view thereof, the left side elevational view being a mirror image thereof;

FIG. 4 is a bottom plan view thereof; and,

FIG. 5 is a front elevational view thereof.

The broken line showing portions of the transparent bumper guard and of the exemplary straps with buckles do not form part of the claimed design.
